P. WEYDERT

BRAKE STAFF LOCK

Filed May 1, 1925

Fig. 2. Fig. 3.

UNITED STATES PATENT OFFICE.

PETER WEYDERT, OF ESCANABA, MICHIGAN.

BRAKE-STAFF LOCK.

Application filed May 1, 1925. Serial No. 27,322.

My present invention has reference to an operating staff for the brake drums of flat cars, such as are employed in hauling logs and the like.

5 My improvement is to be considered a safety device for operating brake drums, as the staff thereof drops through the drum when the brake is not to be operated, so that the said staff offers no obstructions which 10 are liable to trip trainmen with fatal results and also wherein, when the staff is brought to operative position, no injury will be inflicted to the operator.

A further object is the provision of a 15 brake mechanism for open cars which includes a brake drum having a brake staff movable therethrough and provided with means at its lower end for engaging means in the bottom of the drum so that when the 20 staff is turned to one position it will be locked on the drum and when slightly elevated and turned to a second position will drop through the drum, the upper portion of the staff being provided with the usual 25 operating wheel which rests on the top of the device when the device is in operative position.

With the above broadly stated objects in view, and others which will appear as the 30 nature of the invention is better understood, reference is to be had to the drawings which accompany and which form part of this application.

In the drawings:—

35 Figure 1 is an elevation of the improvement, the brake staff being in operative position.

Figure 2 is a sectional view through the drum with the staff locked thereto, as shown 40 in Figure 1.

Figure 3 is a similar sectional view but showing the staff in lowered inoperative position.

45 Figure 4 is a central vertical longitudinal sectional view through the drum with the staff removed.

Figure 5 is a sectional view on the line 5—5 of Figure 4.

Figure 6 is a view of the lower end of the 50 staff.

As the brakes of open bodied cars are of the well known type I have not deemed it necessary to illustrate the same nor have I illustrated the chain connection between the 55 drum and the brake mechanism.

Referring now to the drawings in detail

the numeral 1 designates the drum associated with the brake mechanism of a car. The drum is suitably mounted for turning but held, in the usual manner from longitudinal movement. The drum, from the lower end thereof, has its bore widened and provided with spaced longitudinal grooves 2 and 3, which have lower angle portions which communicate. These last mentioned 60 portions are indicated for distinction by the numerals 4. The groove 3 is extended the entire length of the widened portion of the bore of the drum; but the said widened portion is formed with transverse passages 5 65 with which the grooves 2 communicate. The passages 5 have inner straight walls 6, and the lower walls 7 provided by the said 70 passages are formed with downwardly directed notches 8, the walls 6 providing one 75 of the side walls of the said notches. Received through the bore of the drum 1 there is a brake staff 9. A hand wheel 10 is 80 screwed on the outer or upper end of the 85 brake staff. The wheel 10 will rest on the top of the drum when the staff is lowered to non-operating position. The staff 9 has its lower end formed with laterally extending oppositely arranged bits 11, and these 90 bits are of a size to be snugly received through the groove extensions 4 and to enter the grooves 2 and 3. A quarter turn of the drop staff when the bits 11 thereof are disposed in a line with the passages 7, will bring the said bits in a line with the notches 95 8. The arrangement of the bits is determined by the contact of the bits with the walls 6. The staff is then permitted to drop so that its bits 11 are brought into the 95 notches 8. The staff is now locked to the 100 drum and the turning of the staff will impart a like movement to the drum. After the brake is operated the staff is raised in the drum to bring its bits 11 opposite the 105 passages 5. The upward movement of the staff, through the drum, is limited by the contact of the bits with the upper wall 12 of the passages, the same also providing the terminal wall of the grooves 3. The staff 110 is then turned so that its bits 11 will contact with the opposite side walls provided by the grooves 3, which brings the bits in a position to be received through the grooves 2 and 3. A release of the head will permit the shaft 115 to drop by gravity through the drum 1 and the downward movement of the staff is limited, as above stated, by the contact of its

wheel 10 with the upper end of the drum 1. It is, of course, to be understood that the wheel 10 is removed from the staff 9 before the said staff is passed through the bottom 5 of the drum. The wheel 10, when secured on the staff, limits the downward movement of the staff through the drum and the bits 11, when brought into contact with the walls 12, of the passages 5, will limit the outward 10 movement of the staff through the drum. Thus it will be noted that the staff is at all times associated with the drum.

The simplicity of my improvement, the easy manner in which the same is operated 15 and the life saving propensity thereof will be understood and fully appreciated by those skilled in the art to which this invention relates so that a further detailed description thereof is not believed necessary.

20 Having described the invention, I claim:
1. In a device for the purpose set forth, a revoluble brake drum, which is held from longitudinal movement, a wheel operated staff designed after being inserted in the 25 drum to normally drop by gravity through the drum to bring the wheel thereof to rest on the top of the drum, said staff having its outer end formed with bits, said drum having its lower end provided with grooves to 30 receive the bits of the staff therethrough when the staff is drawn outwardly through the drum, said drum having transverse passages communicating with the respective grooves and terminating in notches in which

the bits of the staff are received when the 35 said staff is turned to bring its said bits through the passages and the staff is permitted to drop in the drum to lock the staff to the drum, and to sustain the wheel end of the staff elevated above said drum.

2. A revoluble brake drum which is held from longitudinal movement and a staff 40 adapted to be inserted through the lower end of the drum and thereafter to have a wheel secured thereon, and the wheel of the said staff being designed to normally rest in the top of the drum, said drum having its bore, at its lower end widened and formed with longitudinal grooves arranged in pairs 45 which communicate, said portion of the staff having passages, having oppositely directed transverse passages communicating with the grooves and the drum being notched longitudinally in a line with the inner 50 and lower walls provided by the passages and the brake staff having oppositely directed bits thereon designed to be received in the grooves, when the staff is drawn outwardly through the drum, to be limited in such movement by the contact of the bits 55 with the upper walls provided by the passages and to be guided into the notches when the staff is turned to bring the bits into contact with the inner walls of the passages, as 60 and for the purpose set forth.

65 In testimony whereof I affix my signature.

PETER WEYDERT.
